UNITED STATES PATENT OFFICE

2,283,972

STARTER SWITCH

Charles Chirelstein, Newark, N. J.

Application August 9, 1941, Serial No. 406,216

1 Claim. (Cl. 200—113)

The invention here disclosed relates to starter switches for gaseous discharge devices.

Special objects of the invention are to make it possible to use a greater amount of "getter" medium and thus to obtain higher effectiveness, through a longer period of use.

It has been found that the amount of "getter" which can be used is more or less critical and limited in value. Also, that if more getter could be used, the operation of the switch would be better and it would continue effective over a longer period of time.

The present invention involves the discovery that a proportion of aluminum added to the "getter" medium overcomes the critical limitations mentioned and enables the use of more getter material—as an actual practical example, double the amount.

Particular details of the invention are hereinafter pointed out and broadly claimed.

The drawing accompanying and forming part of the specification is illustrative of one typical embodiment of the invention. Details however may be modified and changed all within the true intent and broad scope of the invention as hereinafter defined and claimed.

Fig. 1 is a broken part sectional side elevation of a form of starter switch incorporating features of the invention.

Fig. 2 is a sectional view taken on the line 30 2—2 in Fig. 1.

As shown in the figures, the switch may comprise a bowed bimetallic strip 1, supported at one end on the angularly offset end 2, of an electrode 3, in position for its free end to engage the angularly offset portion 4 of the second electrode 5, the latter further having an extended bent arm 6, mounting the plate 7, cupped at 8, to carry the "getter" material.

The plate or "pill" as it is known in the trade, is faced downwardly and supported substantially centrally over the loop of the bimetal.

The switch parts described are carried by a press 9, sealed into the container or envelope 10.

Barium and magnesium are approved as "getter" materials, barium in particular.

It has been found that the amount of barium

which can be used, can be very greatly increased by using nearly or approximately half as much aluminum.

In a present preferred embodiment, the proportions are as follows:

	Per cent
Barium	43
Magnesium	37
Aluminum	19 to 20

This proportion of aluminum enables a pill to be used of double or even three times the size previously considered possible.

The greater amount of active material thus made available provides a switch which is faster in operation, at lower temperatures and at lower voltage.

The aluminum-barium-magnesium combination is particularly effective in a neon atmosphere diluted with approximately .5% krypton.

The lateral offset 2 serves to support the bimetal substantially centered over the end of the press and the lateral offset 4 of the second electrode provides a switch contact in position to be engaged by the extreme free end of the bimetal. The inwardly offset portion 6 is disposed substantially centrally over the end of the press and in general parallelism with the free arm of the bimetal. The portion 6, extending transversely of the press and the inward offset 11, provides a rugged central support for the plate. The bends in the electrodes, in addition to locating the parts in the desired relations, described, add a desirable degree of stiffness and rigidity.

What is claimed is:

In a starter switch, wherein a bowed bimetallic switch element operates in an atmosphere of rare gases within a sealed container, an active medium sealed within said container and including barium, magnesium and aluminum, the aluminum being present in the proportion of approximately 20% and thereby enabling the use of a high proportion of barium, the latter being present in the proportion of approximately 43% and the magnesium in the proportion of approximately 37%.

CHARLES CHIRELSTEIN.
